UNITED STATES PATENT OFFICE.

ALBERT E. JOHNSON, OF BEVERLY, MASSACHUSETTS, ASSIGNOR TO UNITED SHOE MACHINERY COMPANY, OF PATERSON, NEW JERSEY, A CORPORATION OF NEW JERSEY.

INSOLE-LIP-SEWING MACHINE.

1,171,723.

Specification of Letters Patent. Patented Feb. 15, 1916.

Application filed November 4, 1914. Serial No. 870,206.

To all whom it may concern:

Be it known that I, ALBERT E. JOHNSON, a citizen of the United States, residing at Beverly, in the county of Essex and State 5 of Massachusetts, have invented certain new and useful Improvements in Insole-Lip Sewing Machines; and I do hereby declare the following to be a full, clear, and exact description of the invention, such as will 10 enable others skilled in the art to which it appertains to make and use the same.

This invention relates to sewing machines for forming insoles and more particularly to sewing machines for forming what are 15 known commercially as "Economy" insoles.

In forming the Economy type of insole the blank is treated by slitting its face to form a channel and by slitting the edge to form a feather, these operations producing 20 two independent contiguous flaps at the margin of the blank. The two flaps thus formed are turned up from the channel and the feather and secured together to form a single compound lip. Thereafter reinforcing fabric such as canvas is applied to the 25 face of the insole and to the lip.

The present machine contemplates an improvement in the formation of insoles of the general character described and relates 30 to the step of bringing the channel and feather flaps together to form a single compound lip. Heretofore the two flaps have been secured together either by cement or by a line of stitches formed in the usual 35 manner by means of well known stitch forming mechanism in sewing machines suitably modified to adapt them to this particular class of work, including, among other features, a pressure device engaging the insole 40 to hold it in position to receive the stitches through the two flaps. It has been found in practice that owing to the heavy pressure exerted on the insole by the sole positioning device, and the flimsy character of the stock 45 engaged by the feeding device, namely the flaps, some difficulty has been experienced in feeding the insole properly through the machine.

The object of the present invention is to 50 provide a novel mechanism for automatically relieving the pressure of the sole positioning device, or pressure roll, on the insole during the time the insole is being fed, thus entirely overcoming any friction 55 exerted by the device on the sole at this time.

In accordance with this object the invention contemplates the provision of a stop attached to the outer end of the lever for raising the presser foot the upward movement of the stop and consequent outward 60 movement of the pressure device through the usual connecting levers to the presser foot raising lever, being controlled by a movement of the feed mechanism.

In the illustrated embodiment of the invention the stop is directly engaged and moved by the usual four-motion feed bar, that is, the stop is lifted and the pressure device moved outwardly by the upward movement of the feed bar just before the 65 feed foot grips the work preparatory to feeding. Thus the pressure device is released from the work during the period when the feed foot is performing its feeding function and is returned to its sole positioning location when the foot drops and the stitch forming mechanism becomes operative.

To the accomplishment of the above object and such others as may hereinafter appear, 80 the invention comprises the devices, combinations and arrangements of parts hereinafter described and particularly pointed out in the appended claims.

The preferred form of the invention is 85 illustrated in the accompanying drawings in which:

Figure 1 is an end elevation of a Willcox and Gibbs domestic sewing machine adapted to securing together the two contiguous flaps 90 of an insole, having the improved pressure and positioning device releasing mechanism fitted thereto, and Fig. 2 is a rear elevation, enlarged, of the pressure device releasing mechanism and its associated parts, the 95 feed bar, and an insole being fed, being shown in section.

In the embodiment of the invention illustrated in the drawings, the Willcox and Gibbs sewing machine there shown is provided with the usual stitch forming mechanism including a straight eye-pointed needle 2 and a rotary thread hook or cast off 4. The thread hook is rotated by being mounted directly upon the driving shaft 6 and the needle bar is reciprocated in guides on the frame by the oscillations of a pivotally mounted lever 8 actuated from an eccentric on the driving shaft 6, all as usual. A four-motion feed mechanism including a feed 105

bar 12 pivoted at 14 to the machine frame is operated in the usual manner by an eccentric 16 on the end of the driving shaft 6. The feed bar 12 is provided with an extension 13 for guiding its movement, said extension being held to the frame by a washer 15. A presser foot 18 is carried by the usual presser foot bar 20. The presser foot is held down by a spring 62 which bears on a loose collar 63 resting on the fixed collar 64 on the presser foot bar.

Instead of the usual large flat work table provided in domestic sewing machines in the present machine the work table 24 is made quite small as shown in Fig. 1. It is removably held in the casting 25 by a screw 19, with its front edge in a plane but slightly in advance of the path of operation of the needle 2. This change in the size and location of the work table is to permit it to support the two upturned flaps of an insole in such position relative to the stitch forming mechanism as properly to receive a line of stitches. When in working position the edge flap of the insole rests upon the work table, the front edge of the work table pressing well into the shoulder at the base of the feather, and the channel flap is pressed upon by the presser foot 18. An insole in position during the feed movement is illustrated in Fig. 2.

The small area of the work table leaves the thread hook 4 exposed and owing to the position of the insole in the machine unless some protection be provided the thread hook, in its rotation, is liable to injure either the marginal portion of the sole by engagement therewith or the hand of the operative who directs the feed of the work through the machine. To prevent such injury the thread hook is provided with a cap or guard 28 removably supported in the casting 25, which incloses the upper portion of the path of movement of the thread hook, thus effectively housing it and preventing its coming in contact with either the work or the operative.

In order to maintain the two flaps of the insole in stitch receiving position during the operation of the stitch forming mechanism, the machine is also provided with a sole positioning device, or presser roll, comprising a roll 32 adapted to exert pressure on the unchanneled face of the insole at a point opposite the flaps. This roll is mounted upon one arm 34 of a bell-crank lever which is pivoted at 35 in a bearing located upon the machine frame at a point below the work table. This mounting of the work guide provides for an unobstructed space above and in front of the work table, thereby permitting the insole readily to be inserted and removed, and also provides for a free and easy manipulation of the insole by the operative during the stitching opera-

tion. The guide roll 32 is held in working position by means of a strong, coiled spring 37 connected by its ends to a pin 33 in the lever arm 34 and an eye-bolt 33' mounted upon the machine frame. The other arm 36 of the bell-crank lever which supports the work guide is connected by means of the well known yoke and sliding block to the forwardly extending arm 38 of a second bell crank lever pivoted at 39 in a bearing 75 formed on the casting 25. The rearwardly extending arm 40 of this latter bell-crank lever has depending therefrom a chain 42 which is connected to any usual or convenient form of operating treadle (not shown). With this construction, when the treadle is moved in a direction to depress the bell-crank arm 40 motion is communicated from the bell-crank arm 38 to bell-crank arm 36 in a direction to move the guide roll outwardly into a position to permit insertion or removal of the work. When the treadle is released, the spring 37 returns the guide roll to its working position.

As the presser foot 18 must be lifted before the work can readily be removed from the machine, means may conveniently be provided for lifting the presser foot at the time the guide roll 32 is removed from working position. To this end a lever 44 is pivoted at 39 and is adjustably connected at its rear end in a well known manner to the bell-crank arm 40, its forward end extending to a position beneath the lower end 46 of the presser foot bar. The lever 44 is preliminarily adjusted to a position to allow for changes in the position of the guide roll, due to the varying thickness of the work as it is fed through the machine without engagement of the lever 44 with the shoulder 46. The space provided for this purpose, however, though sufficient to prevent an inopportune lifting of the presser foot, is not sufficient to prevent the proper operation of the lever 44 when the bell-crank arm 40 is depressed by means of the treadle.

The features of the present machine relating to stitching the two flaps together, heretofore described, are not claimed herein as they are more fully described and claimed in detail in my United States Patent No. 1,089,473 dated March 10, 1914, to which reference may be had for a complete explanation.

Referring now more particularly to Fig. 2 which illustrates the novel feature of the machine forming the subject matter of the present invention, it will be seen that mounted on the outer end of the lever 44 is a screw threaded lug 51 which holds an adjustable stop 50. In the illustrated embodiment of the invention the stop 50 is so situated that it will be engaged by the feed bar 12, in a recess 52, just in front of the

- mounting of the feed foot. During the stitch forming operation the feed bar 12 is in its lowest position, and the lower end of the stop 50 is not in contact with it. The stop is preliminarily so adjusted relative to the feed bar that, when the eccentric 16 raises the toothed feed foot and just before it completes its upward movement and is ready to move forward the stop will be engaged by the feed bar. This position is clearly shown in Fig. 1. Further upward and forward movement of the feed bar for the feeding operation will raise the lever 44 and by its connection with the bell-crank 38—40 and 34—36 the presser roll 32 will be moved outward and release its pressure on the insole, as clearly shown in Fig. 2. By virtue of this construction while the insole is being fed forward the friction and drag of the roll 32 is removed. The adjustment of the lever 44 with relation to the shoulder 46 to allow for changes of the guide roll due to varying thickness of work is explained above, and in making this adjustment allowance is made for sufficient play of the lever 44 so that the slight lifting of this lever due to the movement of feed bar 12 to remove the pressure of the presser roll will not permit an inopportune lifting of the presser foot 18.
- In the operation of the machine the work is inserted by pressing on the treadle which, operating through the bell-crank 40—38, raises the presser foot from the work table and throws the presser roll 32 outward, thus opening up the work holding mechanism and allowing the insole to be placed in the proper position. Just before the four-motion feed bar completes its upward stroke to grip the work, the feed bar engages the adjustable stop 50 and the presser roll 32 is moved outward. Thus pressure from the roll on the insole is removed during the feeding or forward movement of the feed foot. When the feed bar falls at the completion of its feeding stroke the presser roll is again drawn against the insole by the spring 37. The presser roll is thus released from its pressure on the work during the forward stroke of the feed bar but presses against the work under the full force of the spring 37 during the backward stroke of the feed bar, that is, at the time the stitches are formed.
- The nature and scope of the invention having been indicated and its preferred embodiment specifically described, what is claimed as new, is:
1. A machine for securing together the two contiguous flaps of an insole having, in combination, means for inserting fastening devices in said flaps, supporting means for the flaps, a pressure device bearing on the face of the insole opposite the flaps to hold the insole flaps in position to receive the fastening devices, mechanism for moving said device into and out of contact with the insole, reciprocating insole feeding means, and means operatively connected to said mechanism and controlled by the movement of said feeding means for releasing the pressure device during the feed.
  2. A machine for securing together the two contiguous flaps of an insole having, in combination, means for securing the flaps together, flap clamping means, a pressure device to hold the flaps in position to be clamped, insole feeding means, and means operated by a movement of the feeding means to release the pressure device during the feed.
  3. A machine for securing together the two contiguous flaps of an insole having, in combination, means for securing the flaps together, a work table to support the flaps, a presser foot to clamp the flaps on said table, a pressure device to hold the insole flaps in position to be clamped, a feeding mechanism, and means to release the pressure of said device during the feed while the presser foot remains in engagement with the flaps.
  4. A sewing machine for securing together the two contiguous flaps of an insole having, in combination, stitch forming mechanism, clamping means to hold the flaps, a presser roll to hold the insole flaps in stitch receiving position, a feeding mechanism, an operating lever connected with the presser roll, and a stop coöoperating with said lever and adapted to be engaged by said feeding mechanism to operate said lever and release the presser roll from the insole during the feed.
  5. A sewing machine for securing together the two contiguous flaps of an insole having, in combination, stitch forming mechanism, a flap clamping mechanism, a pressure device to hold the flaps in stitch receiving position, an operating lever with a stop connected to said pressure device, and a four-motion feed bar adapted to engage said stop prior to its feeding movement and operate said lever to release the pressure device from the insole during the feed.
